SANDER PIPE SUPPORT

Martin P. Blomberg, Hinsdale, Ill., assignor to
General Motors Corporation, Detroit, Mich., a
corporation of Delaware

Original application October 6, 1939, Serial No.
298,197. Divided and this application January
2, 1941, Serial No. 372,803

8 Claims. (Cl. 291—41)

This application is a division of my co-pending application, Serial No. 298,197, filed October 6, 1939.

The invention relates to sander devices for railway vehicles, and has to do more particularly with the supporting and securing of the sander pipe nozzle through which sand may be discharged onto the track adjacent the wheels when the brakes are being applied.

Since it is important that the discharge end of the sander pipe nozzle be located as close as possible to the wheel and to the track in order to be most effective, it has been found unsatisfactory to support it on some part of the brake rigging or other portion of the vehicle which changes its angular position with respect to the wheel or track when the brakes are applied or adjusted, because the discharge end of the nozzle will then be tilted and consequently will be moved relative to the wheel or track so that it is likely to be too close to or too far away from those members.

It is therefore an object of this invention to provide a support for a sander pipe nozzle on a part of the brake rigging, which support is so devised that it will retain the nozzle in the same angular relationship to and at substantially the same distance from the wheel and the track at all times, regardless of whether the brakes are applied or not, or whether the brake shoes are new or are worn so that the rigging must be adjusted to take care of such wear. This is accomplished by supporting the nozzle on the slack adjuster nut, which part in the type of brake rigging shown in said application Ser. No. 298,197, does not change its angular position relative to the wheels or track when the brakes are applied or adjusted.

The above and other objects of the invention will be more readily understood by referring to the specification and accompanying drawing, in which:

Fig. 1 is a side elevational view of one end of a railway car truck, showing my improved sander pipe support associated with the brake rigging.

Fig. 2 is a sectional view, taken on the line 2—2 of Fig. 1, showing the parts on a somewhat larger scale.

Fig. 3 is a sectional view, taken on the line 3—3 of Fig. 2.

Fig. 4 is a sectional view, taken on the line 4—4 of Fig. 3.

The reference numeral 9 designates the platform or body of a railway car to which the truck frame 10 is pivotally connected in the usual man-

ner by a center plate and king pin connection which is not shown. Axle 12 on which wheels 14 are mounted is journalled in the usual manner in journal boxes 16, and 18 is an equalizer bar, the ends of which rest on top of the journal boxes. The brake rigging shown is of the clasp type, and consists of brake shoes 20 and 22 adapted to be forced against opposite sides of the wheels, the shoes being carried upon brake heads 24 and 26. The brake head 24 is pivotally mounted upon a live truck lever 28 at the point 30, and is supported by a pair of hangers 32 which are pivotally secured to the truck frame at 34, while the brake head 26 is pivotally connected at 36 to a dead truck lever 38 which is pivotally supported from the truck frame at 40.

The lower ends of the levers 28 and 38 are connected together by a pair of tension rods 42 and 44 which extend on opposite sides of the wheel, the right hand ends of the tension rods being connected to the bottom of the lever 28 by a bolt 46 which passes through holes formed in the lever and in the tension rods. The opposite ends of the tension rods are connected together and held in proper spaced relation to each other by a member 50 having trunnion portions 52 formed on it, which trunnion portions extend through holes provided in the ends of the tension rods, the latter being drawn against shoulders 54 on the member 50 by nuts 56 which are threaded onto the ends of the trunnion portions.

Formed on the member 50 is a sleeve portion 58, which as shown in Fig. 3, is open at its right hand end, the opposite end 60 being closed except for a hole 62 formed therethrough. Rotatably supported in this hole is the shank 64 of a screw 66, there being a hexagon-shaped head member 68 secured to the shank by a pin 70, this head member being adapted to bear against the end 60 of the sleeve to prevent axial movement of the screw relative to the sleeve in the one direction, while a flange 72 formed on the screw engages the inside surface of the end 60 to prevent axial movement of the screw in the opposite direction.

The lower end of the lever 38 is formed in the shape of a yoke having legs 82 and 84 which fit between the tension rods 42 and 44, there being a tubular-shaped extension 86 formed on the leg 84 to make the yoke as wide as the space between the tension rods. Located between the legs of the yoke is the end 88 of a slack adjuster nut 90, there being a threaded portion 92 at the opposite end of the nut into which the screw is threaded. The end 88 of the slack adjuster nut is held in place 55 between the legs of the yoke on the lever 38.

by a bolt 94 which passes through slots 96 formed in the tension rods, through holes formed in the legs of the yoke and through a hole formed in the end 88 of the slack adjuster nut, there being suitable bushings of anti-friction material provided in these holes at the points where the bolt bears to reduce friction at these points.

Located between the head of the bolt 94 and the tension rod 42 is a washer 98 having a projection which extends into the slot 96 in the rod, the projection having flat sides which are adapted to bear against the edges of the slots for sliding engagement therewith, the width of the projection between the flat sides being slightly less than the width of the slot, this construction being shown and more fully described in said application Ser. No. 298,197. A similarly shaped washer 104 fits in sliding engagement in the slot in the tension rod 44, being held in that position by a compression spring 106 located between that washer and a nut 108 threaded onto the end of the bolt 94, the spring serving to keep the parts in tight enough engagement with each other to prevent rattling, while at the same time permitting them to slide relative to each other. The central portion of the slack adjuster nut is slidably supported in a bushing 110 which is pressed into the open end of the sleeve 58.

The slack adjuster is operated by turning the head member 68 by hand or by means of a wrench, thus rotating the screw 66, which causes the slack adjuster nut 90 to move axially in the sleeve 58. Since the bolt 94 extends through the end 88 of the slack adjuster nut, it is caused to move in the slots 96 in the tension rods, and since the bolt passes through the openings in the legs 82 and 84 on the bottom of the brake lever 38, the latter is also caused to move, thereby changing the position of the brake shoe with respect to the wheel.

Extending inwardly toward the wheel and downwardly at an angle from the end 88 of the slack adjuster nut is a projection 118 upon which is supported a sander pipe nozzle 120, to the upper end of which is connected a hose 122 which leads upwardly to a pipe 126 supported in any suitable manner, such as by straps 128, to the underside of the platform or body 9 of the car. The opposite end of the pipe 126 communicates with the sand box (not shown) which is located within the car body, there being the usual valves provided to control the flow of sand to the track when desired.

The sander pipe nozzle 120, which extends between the legs 82 and 84 of the brake lever 38, is supported on the projection 118, being clamped against the latter by means of U-bolts 130 which extend through holes 124 formed in the projection, nuts 132 being threaded onto the ends of the U-bolts. Interposed between the U-bolts and the nozzle is a curved member 134, the inner surface of which conforms to the curvature of the outside of the sand pipe, and the outer surface of which has grooves 136 formed in it, the curved portions of the U-bolts fitting within the grooves. The function of the curved member 134 is to distribute the clamping pressure of the U-bolts over a substantial area of the nozzle to avoid flattening or otherwise deforming it which might result if the clamping action of the U-bolts were applied directly to the nozzle.

The lower end of the nozzle 120 is bent so that it extends toward the flange of the wheel, to cause the sand which is discharged therefrom

to be directed into the pocket formed between the flange and tread of the wheel and the top of the track, which reduces the possibility of the sand being blown off the track by side winds.

5 A washer 138 is welded or otherwise secured to the nozzle a short distance above the lower end thereof for the purpose of preventing water which may run down the sand pipe from reaching the lower end of the nozzle where in cold weather it might freeze and stop the flow of sand therefrom.

One important advantage of supporting the sander pipe nozzle on the slack adjuster nut is that since the latter moves in a horizontal plane 10 and parallel to the track, the lower end of the nozzle does not change its angular position when the brakes are applied or adjusted to take care 15 of wear and consequently always remains at substantially the same distance above the track, which would not be the case if it were supported on the brake lever or some other part of the 20 brake rigging which changed its angular position when the brakes were applied or were adjusted to compensate for wear of the shoes.

25 Another advantage of supporting the sander pipe nozzle on the slack adjuster nut is that this results in the securing means being located in a 30 position where it will be easily accessible to permit adjustment of the position of the lower end of the nozzle relative to the top of the track.

While a specific embodiment of the invention has been shown and described, it will be understood that various changes in the details of construction and arrangement of parts may be made 35 without departing from the spirit and scope of the appended claims.

I claim:

1. In a device of the class described, the combination of a brake rigging including a brake lever, a brake shoe supported by said lever, and a pair of tension rods, slack adjusting means connecting the lower end of said lever to said tension rods, said slack adjusting means being adapted to move axially in a horizontal plane when the brakes are applied or adjusted, and a sander pipe nozzle supported on said slack adjusting means below said brake shoe.

2. In a device of the class described, the combination of a brake rigging including a brake lever, a brake shoe supported by said lever, and a pair of tension rods, slack adjusting mechanism connecting the lower end of said lever to said tension rods, said slack adjusting mechanism being adapted to move axially in a horizontal plane when the brakes are applied or adjusted, a sander pipe nozzle supported on said slack adjusting mechanism below said brake shoe, and means adapted to secure said sander pipe to said slack adjusting mechanism.

3. In a device of the class described, the combination of a brake rigging including a brake lever, a brake shoe supported by said lever, and a pair of tension rods, a slack adjuster nut connecting the lower end of said lever to said tension rods, said slack adjuster nut being adapted to move axially in a horizontal plane when the brakes are applied or adjusted, and a sander pipe nozzle supported on said slack adjuster nut below said brake shoe.

4. In a device of the class described, the combination of a brake rigging including a brake lever, a brake shoe supported by said lever, and a pair of tension rods, a slack adjuster nut connecting the lower end of said lever to said ten-

sion rods, said slack adjuster nut being adapted to move axially in a horizontal plane when the brakes are applied or adjusted, a sander pipe nozzle supported on said slack adjuster nut below said brake shoe, and means adapted to secure said nozzle to said slack adjuster nut.

5. In a device of the class described, the combination of a brake rigging including a brake lever, a brake shoe supported by said lever, and a pair of tension rods, a slack adjuster nut connecting the lower end of said lever to said tension rods, said slack adjuster nut being adapted to move axially in a horizontal plane when the brakes are applied or adjusted and a sander pipe nozzle supported below said brake shoe on said slack adjuster nut in order that the lower end of said nozzle will remain at a constant distance above the track when the brakes are being applied or adjusted.

6. In a device of the class described, the combination of a brake rigging including a brake lever, a brake shoe supported by said lever, and a pair of tension rods, slack adjusting mechanism adjustably connecting the lower end of said lever to said tension rods, said slack adjusting mechanism being adapted to move axially in a horizontal plane when the brakes are applied or adjusted, said slack adjusting mechanism having a projection formed thereon below said brake shoe,

and a sander pipe nozzle supported on said projection.

7. In a device of the class described, the combination of a brake rigging including a brake lever, a brake shoe supported by said lever, and a pair of tension rods, a slack adjuster nut adjustably connecting the lower end of said lever to said tension rods, said slack adjuster nut being adapted to move axially in a horizontal plane when the brakes are applied or adjusted, said nut having a projection formed thereon below said brake shoe, a sander pipe nozzle supported on said projection, and means adapted to secure said nozzle to said projection.

10 15 20 25 8. In a device of the class described, the combination of a truck frame, a brake lever supported from said frame, a brake shoe supported by said lever, said lever having a pair of legs at its lower end and a slack adjuster nut located between and pivotally connected to said legs, said slack adjuster nut being adapted to move axially in a horizontal plane when the brakes are applied or adjusted, a projection formed on said nut, a pair of tension rods adjustably connected to the lower end of said lever by said nut, a sander pipe nozzle extending between the legs of said brake lever and supported on said projection, and means adapted to secure said nozzle to said projection.

MARTIN P. BLOMBERG.
